UNITED STATES PATENT OFFICE.

CLAUDE LESTER WALLING, OF SHERBURNE, NEW YORK.

MACHINE FOR HANDLING SNOW OR THE LIKE.

Application filed September 3, 1925. Serial No. 54,295.

To all whom it may concern:

Be it known that I, CLAUDE LESTER WALLING, a citizen of the United States, residing at Sherburne, in the county of Chenango and State of New York, have invented certain new and useful Improvements in Machines for Handling Snow or the like, of which the following is a specification.

My invention relates to a machine for gathering up snow, from the streets or the like, and delivering the same into a wagon or to any other desired point.

An important object of the invention is to provide a machine of the above mentioned character, having means whereby pneumatic action is employed for the proper manipulation of the snow.

A further object of the invention is to provide means whereby the snow is caused to travel continuously through the outer portion of the drum of the machine, until it is discharged by the blower fan, without liability of clogging within the drum.

A further object of the invention is to provide a machine of the above mentioned character, which is of simple construction, and is strong and durable.

Other objects and advantages of the invention will be apparent during the course of the following description.

In the accompanying drawings forming a part of this specification and in which like numerals are employed to designate like parts throughout the same,

Figure 1 is a side elevation of a machine embodying my invention,

Figure 2 is a plan view of the same,

Figure 3 is a central vertical longitudinal section through the blower mechanism,

Figure 4 is a transverse section taken on line 4-4 of Figure 3, and,

Figure 5 is a similar view taken on line 5-5 of Figure 3.

In the drawings, wherein for the purpose of illustration is shown a preferred embodiment of my invention, the numeral 10 designates a chassis, mounted upon wheels 11. Mounted upon this chassis is a motor, such as an internal combustion engine 12, which may be suitably geared to the rear wheels 11, to propel the machine, if desired.

The machine further embodies a fan or blower casing 13, the rear end of which is closed by a head 14, and the forward end of which is closed by a head 15, suitably secured therein. This casing is arranged

transversely of the chassis 10 and is rigidly attached thereto by brackets 16 or the like. The fan casing 13 is cylindrical and is provided with an outlet pipe 17, which leads 60 therein at a tangent, and is adapted to deliver the snow to a suitable point, such as into a wagon 18.

The numeral 19 designates a conveying drum, which is circular in cross section, 65 tapered, and increases in diameter toward the fan casing 13. The large end of the tapered drum 19 is suitably held within an opening 20, formed in the head 15. The forward end of the tapered drum 19 receives an annular head 21, rigidly attached therein, by any suitable means.

The numeral 22 designates an upright, 75 rigidly mounted upon the chassis 10, and disposed adjacent to the annular head 21. The upright 22 may be bolted or rigidly attached to the head 21, as is obvious. The numeral 23 designates a take up or inlet pipe, provided at its forward end with a flaring mouth 24. At its rear end, this pipe has a horizontal portion 25, extending through an opening in the upright 22 and through the annular collar 21, and discharging into the smaller end of the tapered drum 19. The pipe 23 carries a collar 24', 80 rigidly attached thereto, which is secured to the upright 22 by screws 25', or the like. 85

The numeral 26 designates a horizontal longitudinal drive shaft, the rear end of which is journaled in a bearing 27, fixed to the head 14, while its forward end extends through a gland 28, and is journaled in a bearing 29, mounted upon the transverse end of a frame 30, which is attached to the upright 22 by transverse bars 31, and is also attached to the head 15. This shaft is provided at its rear end with a sprocket wheel 32, driven by a sprocket chain 33, which is driven by the engine 12. The shaft 26 therefore extends centrally longitudinally 90 through the tapered drum 19 and the fan casing 13. 95

Extending longitudinally within the tapered conveyor drum 19 and the fan casing 13, is a rotatable snow feeding device, embodying radially disposed straight blades 34. These blades have inner horizontal edges 35, and outer tapered edges 36, whereby the blades increase in radial width toward their discharge ends. The forward ends of the blades 34 are rigidly mounted upon a ring 37, which is rotatable about the pipe 100 105 110

23. The rear ends of the blades 34 extend to a point adjacent to the head 14, and are rigidly mounted upon a disk 38, which is clamped to the shaft 25 for rotating therewith. Arranged within the group of blades 34 are obstruction or baffle disks 39, clamped to the shaft 25, and rigidly attached to the inner edges of the feeding blades 34. These feeding blades, by revolving rapidly within the tapered conveyor drum 19, act upon the snow causing the same to be thrown outwardly by centrifugal force, thereby effecting the longitudinal travel of the snow toward the large end of the drum, so that the snow is finally discharged into the fan casing 13. A fan is provided within this fan casing, embodying radial fan blades 40, attached to the head 38, and arranged between the blades 34. These fan blades project radially beyond the conveyor blades, as shown. The fan blades function to create a draft which discharges the snow through the outlet pipe 17.

The operation of the machine is as follows:

The intake pipe 23 has its mouth 24 brought into contact with the snow to be removed, while the shaft 25 is rotating at a suitably high speed. The fan blades 40 create an air suction through the pipe 26 and drum 36, which is aided by the conveyor blades 34. The snow enters the small end of the drum 19, in advance of the disk or baffle 39, and is carried outwardly, where it engages the rapidly revolving conveyor blades 34. These blades throw the snow out by centrifugal force, retaining it in contact with the inner wall of the tapered drum 19, whereby the snow travels through this drum and discharges from its large end into the fan casing 13, from which it is blown by the revolving fan, into and through the pipe 17. The obstruction or baffle disks 39 prevent the snow from blowing through the central portion of the drum, and cause it to engage with the conveying blades 34.

It is to be understood that the form of my invention herewith shown and described is to be taken as a preferred example of the same, and that various changes in the shape, size, and arrangement of parts may be resorted to without departing from the spirit of my invention or scope of the subjoined claims.

Having thus described my invention, I claim:

1. A machine for handling snow or the like, comprising a fan casing, a tapered

drum having its large end leading into one end of the fan casing, substantially horizontal conveying blades disposed in a circular group within the tapered drum to act upon the snow therein and throw the same outwardly by centrifugal force, a rotary fan within the fan casing, means to rotate the conveyor blades and fan, and an outlet for the fan casing.

2. A machine for handling snow or the like, comprising a fan casing, a tapered drum having its large end leading into one end of the fan casing, longitudinally tapered substantially horizontal conveying blades disposed in an annular group within the tapered drum to act upon the snow therein and throw the same outwardly by centrifugal force, a rotary fan within the fan casing, means to rotate the conveyor blades and fan, and an outlet for the fan casing.

3. A machine for handling snow or the like, comprising a fan casing, a tapered drum having its large end leading into the fan casing, substantially horizontal conveying blades arranged in an annular group within the tapered drum and extending throughout the major portion of the length of the drum and affording a central passage, spaced baffle disks arranged within the central passage of the group of conveying blades, a fan within the fan casing, means to drive the conveying blades and fan, an outlet for the fan casing, and inlet means for the drum.

4. A machine for handling snow or the like, comprising a fan casing, a drum leading into one end of the fan casing, means to supply snow or the like to the free end of the drum, a group of approximately horizontal conveying blades arranged within the drum and extending through the major portion of the length of the drum, baffle disk or disks within the group of conveyor blades, a fan within the fan casing, means to rotate the fan and blades, and an outlet for the drum.

5. A machine for handling snow or the like, comprising a fan casing, a drum leading into the fan casing, an inlet pipe having its discharge end projecting into the free end of the drum, a ring rotatable about the inlet pipe, a head rotatable within the fan casing, horizontal conveying blades connecting the head and ring, means to rotate the head, a rotary fan within the fan casing, and an outlet for the fan casing.

In testimony whereof I affix my signature.
C. LESTER WALLING.
